(57) **CLAIM**

We claim the ornamental design for a back loaded intraocular lens (IOL) cartridge, as shown and described.

DESCRIPTION

FIG. 1 is a top perspective views of a back loaded intraocular lens (IOL) cartridge;

FIG. 2 is a bottom perspective view of the back loaded intraocular lens (IOL) cartridge of FIG. 1;

FIG. 3 is a left side elevational view of the IOL cartridge of FIGS. 1 and 2;

FIG. 4 is a front elevational view of the IOL cartridge of FIGS. 1 and 2;

FIG. 5 is a rear elevational view of the IOL cartridge of FIGS. 1 and 2;

FIG. 6 is a top plan view of the IOL cartridge of FIGS. 1 and 2; and,

FIG. 7 is a bottom plan view of the IOL cartridge of FIGS. 1 and 2.

The cartridge manages passage of an IOL into an eye.

The broken line showing portion of a back loaded intraocular lens (IOL) cartridge is included for illustrating environmental structure and forms no part of the claimed design.
